Erwin W. Sippel.

BY *E. Sippel*

ATTORNEY

UNITED STATES PATENT OFFICE.

ERWIN W. SIPPEL, OF SEATTLE, WASHINGTON.

CHECK-PROTECTOR.

1,266,872.

Specification of Letters Patent. Patented May 21, 1918.

Application filed November 2, 1916. Serial No. 129,212.

To all whom it may concern:

Be it known that I, ERWIN W. SIPPEL, a citizen of the United States, and a resident of Seattle, county of King, State of Washington, have invented a new and useful Improvement in Check-Protectors, of which the following is a specification.

This invention relates to check protectors by which the amount to be paid is perforatedly printed on the check, note, or other paper, so that no alteration may be made; thus providing a source of protection to both the maker and the payee of the check.

The object of my invention is to provide a check protector of simple construction and operation, and particularly to make the same of light weight and small size so as to adapt it to be carried conveniently in the pocket, for use at all times.

20 The construction and operation of my device are best understood by having reference to the accompanying drawings, in which:

Figure 1 is a top view of my device;

Fig. 2 is a sectional plan view of same;

25 Fig. 3 is an enlarged sectional elevation taken on the line 3-3 of Fig. 2, looking in the direction indicated by the arrows; and

Fig. 4 is a left-end sectional elevation 30 of Fig. 2.

a represents the casing of my device, the base of which in part consists of double plates with an intervening slot or space *b* adapted to receive the check, or note, *c*.

35 In protecting a check, or note, the operator first turns the pointer *d*, which is mounted on a rotatable shaft *e*, until it points at the desired character on the stationary dial *f*. The operator then depresses 40 the finger-key *g*, which is mounted on the lever *h*, and such action marks the paper with the perforate and printed character.

The lever *h* is supported by a spring *i* and is provided with a knob and three horizontal arms *j*, *k* and *l*, as shown in Fig. 2.

45 On the shaft *e*, within the casing, is mounted a type sector *m*. This sector is conveniently made of spring steel and comprises radially extending resilient type bars *n*, independently depressible, and to the under side of the free ends of which are affixed the type characters *o*. These type characters correspond to the characters on the dial *f*. As apparent, the type sector *m* is turned 55 with the pointer *d*, and the type bars *o* are so arranged that the type character corre-

sponding to that pointed at on the dial *f* will be located under the extending arm *j* of the lever *h*. Hence the depression of the lever will cause its arm *j* to bear down on such 60 underlying type bar.

The upper of the two base plates of my device contains an opening *q* (see Fig. 3) which also directly underlies the end of the arm *j* of the lever *h*. Through this opening the registering type bar is depressed, so as to imprint on the check *c*. Directly beneath said opening and on the lower base plate is mounted a platen *r*, having a rough face adapted to cause the impression of the 70 paper on the same, in the imprinting operation, also to perforate the paper. Two ink pads are mounted on the top face of the upper base plate adjacent the opening *q* and so arranged that the type characters *o* will 75 lightly rub over these pads when the sector *m* is turned in correspondence with the movement of the pointer *d*.

To the free end of the arm *k* of the lever *h* is pivoted a pawl *t*, which engages with a 80 ratchet wheel *u*, on the rotatable shaft *v* supported by the spring *x*. When the lever *h* is depressed, for bringing its arm *j* down on the underlying type bar, said pawl *t*, will partially rotate the ratchet wheel *u*, and 85 such partial rotation is transmitted to the two milled, check-spacing or feed wheels *v* also on the shaft *v*. The spacing wheels *v* extend through an opening *w* in the upper base plate, and said wheels are adapted to 90 bear on the check *c* and move the latter. The parts are so arranged that the rotation of the check-spacing wheels *v*, and consequent movement of the check *c*, will take 95 place before the bar of the type to be imprinted touches the check, thereby assuring that the check will be stationary during the imprinting operation.

The arm *l* of the lever *h* extends under the spring *x*, supporting the shaft of the check-spacing wheels *v*, and when it is desired to lift up the latter to permit the removal of the check *c*, the pointer *d* is turned to point to the character R on the dial *f*, called the "release" position of the dial, thus bringing 105 the raised portion *p* of the type-sector *m* (see Figs. 2 and 4) under the arm *j* of the lever *h* and lifting the latter and therewith the arm *l*.

For facilitating the manipulation of the 110 pointer *d*, I provide it with the upwardly projecting handle *y*. In order that the latter

will be out of the way when my device is carried in the pocket, I make the pointer *d* hinged at its middle and provide a recess or cavity in the upper end of the pointer supporting shaft *e*, so that said handle *y* can be folded down, as shown in Fig. 4.

I claim:

1. In a device of the character specified, a dial bearing the characters to be imprinted, a pivoted type-sector having radial resilient, independently depressible type-bars bearing type-characters corresponding with those on said dial, a pointer for said dial fixed on the pivot shaft of said type-sector, the casing being adapted to permit the insertion of a paper under the type-sector, means for depressing one of said type-bars, the parts being so arranged that the type-bar bearing the type-character corresponding with that pointed to on the dial will be positioned for being depressed by said means, a resiliently mounted shaft, a feed wheel mounted thereon, an arm on said depressing means underlying said resiliently mounted shaft, means operated by the type-bar depressing means for progressively rotating said resiliently mounted shaft, and means operating to lift the latter and thereby with said feed wheel when said pointer is pointed to a certain character on said dial.
2. In a device of the character specified, a dial bearing the characters to be imprinted, a pivoted type-sector having radial resilient, independently depressible type bars bearing

type-characters corresponding with those on 35 said dial, a pointer, for said dial, fixed on the pivot shaft of said type-sector, the casing being adapted to permit the insertion of a paper under the type-sector, a lever having 40 a lateral arm overlying one of said type-bars, the parts being so arranged that the type-bar bearing the type-character corresponding with that pointed to on the dial will underlie said lever, a resiliently mounted shaft, a feed wheel mounted thereon, an 45 arm on said lever underlying said resiliently mounted shaft, means operated by the depression of said lever for progressively rotating said resiliently mounted shaft, and means operating to lift the latter and thereby with said feed wheel when said pointer is pointed to a certain character on said dial.

3. In a device of the character described, a dial bearing the characters to be imprinted, a pivoted type sector having radial type bars bearing type characters corresponding with those on said dial, a pointer for said dial fixed on the pivot shaft of said type sector, an actuating lever adapted for causing an impression by that type bar of the 55 type sector in imprinting position, a movable shaft, a feed wheel carried thereby, means co-operating with said actuating lever for revolving said shaft simultaneously with the impression action of said lever, and means adapted to lift the shaft when the pointer is arranged in one position.

ERWIN W. SIPPEL.
